WARE.

LOCOMOTIVE-BOILER FURNACE.

1,138,050.

Specification of Letters Patent.

Patented May 4, 1915.

Application filed December 18, 1911. Serial No. 666,347.

To all whom it may concern:

Be it known that I, CHARLES B. MOORE, a citizen of the United States, and resident of the city of Evanston, county of Cook, and State of Illinois, have invented certain new and useful Improvements in Locomotive-Boiler Furnaces, of which the following is a specification.

My invention relates to improvements in locomotive furnaces and has particular reference to improvements in refractory deflecting walls or baffles otherwise known as arches for the fireboxes of locomotives.

The general objects of my invention are to provide a refractory arch which can be easily and quickly installed in a locomotive firebox without the necessity of any preparatory work being done on the box; to provide an arch which shall be of light weight and low cost; to provide an arch which shall be easy to repair and parts of which can be readily removed to afford easy access to firebox sides and to the flue sheet for necessary repairs thereto; and to provide an arch of a form that shall materially assist in the admixing of the firebox gases.

A special object of my invention is to provide an arch of the character here outlined which shall be particularly adapted for installation in locomotive boilers which are equipped with one or more inclined circulating tubes.

My invention consists in various novel constructions and arrangements and combinations of parts by which the above objects are attained, together with others herein-after appearing, and all as fully described with reference to the accompanying drawings and as particularly pointed out in the appended claims.

In said drawings, which form a part of this specification, I have illustrated a preferred form of my invention and have illustrated its application to locomotive fireboxes having various arrangements of circulating tubes.

Figure 1 of said drawings is a central longitudinal sectional view of a locomotive firebox equipped with a refractory arch the whole embodying my invention; Fig. 2 is a horizontal sectional view of the firebox showing a top plan view of the arch and taken on line 2-2 of Fig. 1; Fig. 3 is a transverse sectional view of the firebox on the line 3-3 of Fig. 1 and showing a rear

end elevation of the arch; Fig. 4 is a transverse sectional view of the arch on the line 4-4 of Fig. 1; Figs. 5, 6 and 7 are views similar to Fig. 4 but showing the invention as applied to fireboxes having different arrangements of circulating tubes; Fig. 8 is an enlarged fragmentary end elevation of the arch more clearly illustrating the interlocking joint between the panel bricks and the supporting bricks; and Fig. 9 is a view in perspective of one of the interlocking panel bricks.

My invention is capable of embodiment in arches occupying various positions in the firebox and having different specific functions and, although I have confined the illustration of the invention to so-called front arches, it should at once be understood that my invention is not thus limited. A so-called front arch usually occupies an inclined position in the firebox extending from side to side thereof and having its forward end in abutment with or arranged close to the flue sheet. The principal function of these arches is to deflect the firebox gases out of their direct line of flow from the grate to the flues and not only cause them to travel back and forth in the firebox and thereby distribute their heat to the whole interior surface of the firebox but also to retain them in the firebox a sufficient time to permit complete combustion to take place before the gases escape through the flues.

A locomotive boiler firebox, as illustrated in the drawings, is made up of a flue sheet 2, side sheets 3, 3, a crown sheet 4 and a rear sheet 5. The firebox has a grate 6 and the rear sheet is provided with a fuel door or opening 7. Flues 8 lead forward from the flue sheet. The firebox illustrated in Figs. 1 to 4 is provided with two inclined water circulating tubes extending from the lower portion of the flue sheet to the upper portion of the rear sheet and serving to increase the circulation of water between the front and rear water legs of the boiler.

A particular feature of my invention resides in an arch which is made up of a number of individual bricks of several different shapes and formed to be supported upon and by the circulating tubes and the side sheets of the firebox. These individual bricks are limited in size by the features that they shall not be too heavy to be handled and placed in position with ease

2
and that they should be small enough to be readily passed through the fire door.

The arches which I have illustrated in the drawings are built of two forms of bricks, *i. e.*, supporting bricks which rest upon and span the tubes, and cover or panel bricks which space the supporting bricks apart and substantially close the openings between them. I arrange the supporting bricks A in transverse rows or lines across the firebox 10 suitably spaced apart to receive and support the panel bricks B. The dimensions of the supporting bricks are determined by the spacing of the tubes in the firebox. Where the spaces to be spanned are comparatively wide, I use two of the bricks placing them together in the form of an inverted V and thus forming a self-supporting span or arch. The length of these bricks being determined by the spacing of the tubes, their cross-sectional area or their weight is determined by the features above mentioned, that is, that they shall be light enough to be readily handled and small enough to be passed into the firebox through the fuel door. I preferably form the supporting bricks substantially square in cross section, that is, making them as deep as they are wide and they are thereby given a sufficient bearing upon the tubes so that when once placed in position they rest securely without rocking on the tubes. I provide the lower ends of these bricks with sockets or grooves A', substantially fitting the curvature of the tubes and adding to the stability of the bricks when once in position.

In the preferred form of my invention I use four of the supporting bricks in each row or line, each of the outer bricks resting at its inner end upon a tube and inclining upwardly and outwardly against one of the side sheets of the firebox and the middle two bricks of the row resting upon the tubes and virtually abutting each other substantially midway between the tubes. I interlock the adjacent bricks together in each row of the supporting bricks to prevent any possibility of their being separated through the jarring effect of the locomotive when running. While I might make use of separate or additional bricks for the purpose of locking the supporting bricks together, I prefer to form the panel bricks B in such a manner that they will perform the functions not only of holding the supporting bricks in their proper spaced relation and closing the openings between them, but will also perform the function of interlocking the supporting bricks in such a manner that the supporting bricks are held against relative movement and the arch, as a whole, is securely retained in its proper working condition.

The ends of the supporting bricks A are provided with ribs or hooks A² which project upwardly and extend from side to side thereof and the panel or cover bricks B are provided with downwardly projecting hooks or ribs B¹ on their ends spaced apart a sufficient distance to span the hooks A² on the abutting ends of adjacent supporting bricks. As shown in the drawings, I place one of the panel bricks B spanning each pair of the abutting ends of the supporting bricks and I proportion the width of the bricks B so that a single brick substantially fills the space between the locking panel bricks and thereby the arch is completed. I preferably form the bricks B with projecting end portions B² adapted to rest upon the upper surface of the supporting bricks and thereby hold the panel bricks in position. It will now be noted that regardless of the shape of the individual bricks, the arch as a whole presents many angularly disposed surfaces and gas-mixing pockets or cavities whereby the effect of the arch in admixing the gases is greatly enhanced. I add to this function of the arch by providing the undersides of the supporting bricks with gas-mixing pockets A³ which extend substantially the length and width of the brick and thereby not only lighten the individual bricks but also provide them with comparatively thin depending flanges A⁴. These flanges, being comparatively thin, quickly attain to the maximum temperature of the firebox and thereby assist in the ignition of the fuel particles and gases. I provide each of the panel bricks B with a depending portion B³ which projects below the upper surfaces of the supporting bricks and provides the brick with end walls or surfaces B⁴ adapted to contact with the sides of the supporting bricks and thereby hold the supporting bricks properly spaced. These depending portions are provided with gas-mixing pockets B⁵ which not only lighten the brick, but provide the arch with additional subsidiary gas-mixing or commingling pockets or cavities B⁶.

In building my arches I place a row or line of the supporting bricks in position resting them upon the tubes and against the flue sheet, the end bricks of the row being placed upon the tubes and leaning against the side sheets. I then place a second line or row of the supporting bricks above and parallel with the first row and hold this second row in position by placing one of the cover or panel bricks upon and between each of the corresponding joints in the two rows of supporting bricks. These panel bricks thus placed retain the two rows of supporting bricks securely in their positions as the panel bricks interlock the adjacent bricks of each row together and the arch being arranged in an inclined position, the weight of the bricks holds the arch down against the flue sheet. I complete this part of the

arch by placing additional panel bricks between those already placed and thus completely close the openings between the spans of supporting bricks. In some instances an arch formed of two rows of supporting bricks and one of panel bricks would be sufficiently high, but usually it is desired that the arch shall be higher than this construction would produce and it obviously can be completed by adding additional rows of supporting bricks and panel bricks until it is as long or high as desired. Usually the arch reaches from the flue sheet to about the center of the firebox and is composed of three spans of the supporting bricks held in position by two intermediate rows of the interlocking panel bricks.

It will now be seen that an arch constructed in accordance with my invention is one in which certain portions may be readily removed without disturbing the arch as a whole when it is necessary to repair the side sheets or flue sheet of the firebox. My arch being composed of individual bricks of a size which are easy to handle, is one which can be placed in position with a minimum expenditure of time and labor. Another feature which is inherent in my novel form of arch is that the arch as a whole does not become a rigid mass after the manner of the ordinary arch, for the reason that the overlapped joints between the various members of the arch do not become cemented together by the slag which forms upon the surfaces of the arch. The arch, therefore, is in a sense flexible, in that it can adjust itself to slight changes of dimensions of the firebox without destructive disintegration.

In Fig. 5 I have illustrated an installation of an arch embodying my invention, in a comparatively wide firebox which is equipped with a single circulating tube. In this instance the space between the tube and the side sheet being too great for the span of a single brick, I arrange two of the supporting bricks in this space forming an inverted V shaped arch after the manner of the middle portion of the arch, as shown in Fig. 2, and I provide inwardly projecting studs 11 on the side sheets 3 for supporting the outer ends of the spans.

In Fig. 6 I have illustrated an installation of the arch in a comparatively narrow firebox which is provided or equipped with a single circulating tube. Here the space between the tube and side sheet is not too great to be spanned by a single brick and I therefore arrange a single supporting brick in this space after the manner of the side or end portions of the spans illustrated in Fig. 2. The supporting bricks in this case are arranged in upwardly and outwardly inclined positions wedgingly engaging the tube and the side sheets.

Fig. 7 illustrates an installation of the

arch in a firebox having three circulating tubes, the outer ones of which are at a higher elevation than the center tube. The weight of the arch in this form is carried entirely upon the tubes, the supporting 70 bricks being arranged in upwardly and outwardly inclined positions similar to the arrangement shown in Fig. 6 except that the bricks instead of being supported upon the side sheets are supported entirely upon the 75 tubes.

It will now be seen that my arch is one which readily accommodates itself for installation in fireboxes having various arrangements of water circulating tubes and 80 that it is one which when once installed remains permanently in position regardless of the destructive jarring effect of the locomotive, when running.

Having thus described my invention, I 85 claim as new and desire to secure by Letters Patent:

1. A locomotive boiler firebox having a plurality of arch tubes, in combination with a refractory arch body resting on said tubes, 90 said body comprising spans which extend between and rest on said tubes, said spans being disposed in spaced apart rows and panel bricks which rest upon two adjacent spans and interlock the two adjacent bricks of 95 each of the two spaces which they engage.

2. A locomotive boiler firebox having a plurality of inclined arch tubes, in combination with a refractory arch body resting upon said tubes, said body comprising a 100 plurality of transverse rows of refractory span bricks spaced apart on said tubes, said bricks being also arranged in longitudinal rows in the firebox and panel or cover bricks resting upon adjacent transverse rows of 105 span bricks and overlapping at each end two span bricks and formed to interlock therewith and prevent relative lateral movement of the span bricks.

3. A locomotive boiler firebox having a 110 plurality of inclined arch tubes, in combination with transverse rows of span bricks supported by said tubes, and a plurality of arch panel or cover bricks in turn supported by said span bricks and certain of said panel 115 bricks interlocking with the said span bricks and preventing the lateral separation of adjacent span bricks.

4. A locomotive boiler firebox having a plurality of arch tubes, in combination with 120 a plurality of transverse rows of bricks spaced apart upon and extending between said arch tubes, and a plurality of arch top forming bricks, through the medium of said transverse bricks being also supported by 125 said arch tubes, said top forming bricks closing the spaces between said transverse bricks and having transverse shoulders on their undersides which serve as stops and spacers for said transverse bricks and cer- 130

tain parts thereof serving to interlock the adjacent bricks in said transverse rows and hold them against separation.

5. A locomotive boiler firebox containing a plurality of inclined arch tubes in combination with two or more rows of refractory span bricks spaced apart upon said tubes and abutting the sides of the firebox, and a plurality of refractory slabs or bricks in the spaces between said rows of span bricks spacing them apart and serving to bind the adjacent bricks in said rows together and preventing them from separating.

6. A locomotive boiler firebox containing a plurality of inclined arch tubes, in combination with two or more substantially identical transverse rows of refractory span bricks abutting the sides of the firebox and longitudinally spaced apart upon said tubes, arch top or panel bricks arranged between adjacent rows of span bricks and resting at each end upon adjacent ends of the bricks in said rows, the ends of said panel bricks and of said span bricks being formed to interlock with each other, and prevent the separation of the span bricks in the firebox.

7. A locomotive boiler firebox containing a plurality of arch tubes, in combination with two or more transverse rows of refractory span bricks abutting the sides of the firebox and spaced apart at different heights upon said tubes, and arch top or cover bricks supported at the ends by adjacent bricks of adjacent spans, the ends of said span bricks being formed to interlock with said cover bricks and be held thereby against separation.

8. In a locomotive boiler firebox having two inclined arch tubes, a refractory arch comprising a plurality of arch bricks in-

clined transversely of the firebox, resting at their lower edges upon the tubes and abutting each other at their upper ends, the adjacent ends thereof being provided with longitudinal ribs, other bricks engaging said ribs and interlocking the first mentioned bricks to prevent their separation transversely of the firebox.

9. In a locomotive boiler firebox, having a group of inclined arch tubes of less width than the firebox, a plurality of transverse rows of span bricks longitudinally spaced of the firebox, each of said spans comprising a plurality of groups of two bricks each, having their adjacent edges resting upon the tubes and extending upwardly and outwardly from the tube, certain of the bricks abutting each other and certain of the brick abutting the side sheets, transverse ribs along the upper outer edges of each said bricks, and cover bricks resting upon two adjacent spans in manner to hold the spans in spaced relation and having portions engaging the ribs of the span bricks to interlock the span bricks against separation transversely of the firebox.

10. In a locomotive fire box arch the combination of an inclined arch tube with two refractory bricks each having an end resting upon said tube and a third refractory brick interlocking the first two against separation upon said tube.

In testimony whereof I have hereunto set my hand, this 5th day of December, 1911, in the presence of two subscribing witnesses.

CHARLES B. MOORE.
